(57) **CLAIM**

What is claimed is the ornamental design for a dual nozzle sprayer, as shown and described.

DESCRIPTION

FIG. 1 is a top perspective view showing the dual nozzle sprayer of Applicant's new design.

FIG. 2 is a bottom perspective view of the dual nozzle sprayer of FIG. 1.

FIG. 3 is a top plan view of the dual nozzle sprayer of FIG. 1.

FIG. 4 is a right side elevation view of the dual nozzle sprayer of FIG. 1, the left side elevation view being an identical mirror image thereto.

FIG. 5 is a bottom plan view of the dual nozzle sprayer of FIG. 1.

FIG. 6 is a front elevation view of the dual nozzle sprayer of FIG. 1; and,

FIG. 7 is a back elevation view of the dual nozzle sprayer of FIG. 1.

The broken lines in the drawings illustrate portions of the dual nozzle sprayer which form no part of the claimed design.
